UNITED STATES PATENT OFFICE.

FRANK BYCROFT KEALL, OF LEICESTER, ENGLAND, ASSIGNOR TO UNITED SHOE MACHINERY COMPANY, OF PATERSON, NEW JERSEY, A CORPORATION OF NEW JERSEY.

EDGE-SETTING MACHINE.

1,161,868.

Specification of Letters Patent. Patented Nov. 30, 1915.

Application filed November 10, 1914. Serial No. 871,302.

To all whom it may concern:

Be it known that I, FRANK B. KEALL, a subject of the King of England, residing at Leicester, in the county of Leicester, England, have invented certain Improvements in Edge-Setting Machines, of which the following description, in connection with the accompanying drawings, is a specification, like reference characters on the drawings 10 indicating like parts in the several figures.

This invention relates to edge setting machines used in the manufacture of boots and shoes, and pertains particularly to the edge setting tool which is rapidly oscillated or reciprocated in contact with the edge of the shoe.

The angle between the edge and the tread face of a shoe sole varies considerably in different styles of shoes, and varies to some extent even in the same shoe, owing to inaccuracies in the edge trimming. The ordinary edge setting tool compels the operator to hold shoes of different styles at different angles while setting their edges, which is inconvenient, and it also misses portions of irregularly trimmed sole edges even when the operator has struck the general angle.

It is the purpose of this invention to meet this difficulty by providing an edge setting tool which will operate on soles differing from one another in the inclination of their sole edges, and also upon sole edges which are differently inclined in different portions, which will do the work more efficiently and better than heretofore, and which can be readily adjusted or removed from the machine without interfering with the adjustment.

In the drawings which show two specific embodiments of the invention:—Figure 1 is a side elevation of an edge setting tool and its holder, showing the holder broken away. Fig. 2 is a plan of the device as shown in Fig. 1, taken perpendicular to the line 2—2, of Fig. 1, the stitch-wheeling disk being removed. Fig. 3 is a section on the line 3—3 of Fig. 1. Fig. 4 is a side elevation partly broken away and in section, of a second form of the invention. Fig. 5 is a section on the line 5—5 of Fig. 4.

The shaft 1 extends from the main body of the machine and is rapidly oscillated in a horizontal plane. It carries the tool holder 2 which is slotted at 3 to receive the edge setting tool. This tool has a body 4

which fits within the slot 3. The body 4 carries the head 5, which is wider than the body 4 and overlaps the holder 2. The front of the head 5 carries the edge setting iron 6, which has the lips 7 at its upper and lower portions, of any desired form, to set the corners of the sole edge. The head 5 also carries the stitch-wheeling disk 8, pivotally mounted at 9.

The lower faces of the lateral portions 65 of the head 5 have recesses 10 which have sharp corners 11 at their front and contact surfaces 12 at their rear. The walls of the holder 2 which inclose the slot 3 are formed with knife edges 13 and cylindrical contact 70 surfaces 14. The knife edges 13 fit in the corners 11 and the surfaces 12 can pivot about the edges 13, and remain in contact with the surfaces 14 which are centered at 13. The edge setting iron is thus capable 75 of adjustment about a horizontal axis at 13. The rear end of the body 4 has a slot 15, by means of which the iron is held in adjusted position.

Threaded in the holder 2 is a screw 16, 80 which carries on its upper end a sleeve 17, having a lateral arm 18, which projects into the slot 15, but does not fill it from side to side. The rotation of the screw 16 will thus adjust the sleeve 17 and the arm 18, 85 and will rotate the body 4 and iron 6 into suitable position to fit the general inclination of the sole edge which is to be operated upon, and the loose fit of the arm 18 in the slot 15 will permit a small oscillation 90 on each side of a mean position to fit varying inclinations of the same sole edge.

Mounted on a pin 19 is a spring 20 the upper end of which is slidably mounted in an arm 21 on the sleeve 17, and holds the 95 arm 18 in the slot 15. The lower end of the spring 20 bears on a friction plate 22 pivoted on the pin 19 and held in contact with the screw 16 by the spring 20. This friction plate prevents accidental motion of the screw 16, owing to the vibration of the device. The handle 23, on the sleeve 17, permits the rotation of the sleeve against the spring 20, until the arm 18 is turned out of the slot 15, whereupon the body 4 can 100 be tipped up until the surfaces 12 and 14 separate, permitting the removal of the body 4 and its iron 6 from the holder 2, and the substitution of another of like formed body, 105 while preserving the adjustment. 110

In the second form, shown in Figs. 4 and 5, the screw 24 is mounted in the rear end of the slot 3 in the holder 2, and carries a sleeve 25 with an arm 26 which extends forwardly in the slot 15 and fits loosely therein, as in the above described type, thus permitting limited motion about an adjusted position. The screw is turned by a knurled head 27. The lower end of the screw 24 has a reduced portion 28 which is rotatably mounted in a transverse shaft 29. The shaft 29 is rotatably mounted in the two walls of the slot 3. It carries on its end a lateral stop arm 30 which co-operates with a recess 31 in the side wall of the holder 2, and which limits the swing of the screw 24 about the axis of shaft 29. A plunger 32, spring pressed by the spring 33 in the recess 34 holds the screw 24 and its sleeve 25 in forward position and its arm 26 in the slot 15, but by pulling back the screw against the spring 33 the arm 26 can be drawn out of the slot 15 and the body 4 and its iron released, without disturbing the adjustment.

25 A plunger 35 is held against the reduced portion 28 by the spring 36 in the hollow screw 37, which is mounted in the shaft 29, and by friction prevents accidental rotation of the screw 24.

30 Having described my invention, what I claim as new and desire to secure by United States Letters Patents is:—

1. In an edge setting machine, a holder, and a tool comprising an edge setting member and a welt indenting member mounted upon said holder and adjustable to different operating positions about an axis substantially parallel to the direction of motion of the tool.

35 2. In an edge setting machine, a holder, and a tool engaging said holder and adjustable relative thereto about an axis substantially parallel to the direction of motion of the tool, said tool being releasable from the holder while preserving the adjustment.

40 3. In an edge setting machine, a holder, and a tool having a face arranged to treat a sole edge engaging said holder and adjustable relative thereto in a plane substantially normal to the tread face of a shoe sole, thereby adapting the tool to use upon soles having differently inclined sole edges.

45 4. In an edge setting machine, a holder, and a tool adjustably mounted in said holder and arranged to have limited motion about an adjusted position.

50 5. In an edge setting machine, a holder, a tool adjustably mounted in said holder, and means for adjusting said tool in said holder, said means permitting limited motions of the tool about the adjusted position.

55 6. In an edge setting machine, a holder, a tool pivotally mounted on said holder, means for adjusting said tool upon said holder about the axis of the pivotal mount-

ing, and means permitting limited motion about said axis in any position of adjustment.

7. In an edge setting machine, a holder, and a tool pivotally mounted on said holder, so constructed and arranged as to be adjustable about the axis of the pivotal mounting and having limited motion about said axis in any position of adjustment.

8. In an edge setting machine, a holder, a tool adjustably mounted upon said holder, and a member for adjusting said tool and for locking it in said holder, said member being operable to release the tool without altering the adjustment.

85 9. In an edge setting machine, a holder, a tool adjustably mounted in said holder, a slot in said tool, and an adjustable member for engaging said tool in said slot in order to adjust said tool and to lock it in said holder, said tool being releasable from said member without altering the adjustment.

10. In an edge setting machine, a holder, a tool adjustably mounted in said holder, and a rotatable member for adjusting said tool and for loosely locking it in said holder.

105 11. In an edge setting machine, a holder, a tool pivotally mounted in said holder, and a pivotal bolt for adjusting said tool about its pivotal axis and for loosely locking it in said holder, said bolt being rotatable about its pivot to permit the removal of said tool and the insertion of another while maintaining the adjustment.

110 12. In an edge setting machine, a holder, a tool pivotally mounted on said holder, a slot in said tool, a screw, and a lug adjustable by said screw and engaging said slot, said lug being removable from said slot without disturbing said screw adjustment.

115 13. In an edge setting machine a holder, a tool adjustably mounted on said holder, a slot in said tool, a screw mounted in said holder, a sleeve on said screw, and a lug on said sleeve engaging said slot, said sleeve being adjustable by said screw to vary the adjustment of said tool.

14. In an edge setting machine, a holder, a tool adjustably mounted on said holder, a slot in said tool, a screw, a lug carried by said screw and adjustable thereby for engaging said tool in said slot, and means for holding said screw in adjusted position and for holding said lug in said slot.

120 15. In an edge setting machine, a holder, a tool adjustably mounted in said holder, a screw mounted in said holder, a lug mounted upon said screw for removably engaging and adjusting said tool, a friction clamp for said screw, and a spring for operating said clamp and said lug.

125 16. In an edge setting machine, a holder, a tool adjustably mounted in said holder, a screw mounted in said holder, and rotatable therein about two axes, and a lug carried

by said screw for adjusting and locking said tool in said holder, said lug being adjusted by rotation of the screw about one axis and brought into or out of contact with the tool by rotation of the screw about the other axis.

17. In an edge setting machine, a holder, a tool mounted therein, a shaft mounted in said holder, a screw mounted in said shaft, a member mounted on said screw for adjusting said tool, and a stop lug on said shaft.

18. In an edge setting machine, a holder, a tool, a knife edge and a bearing surface on one of said elements, and a recess and a second bearing surface on the other of said elements.

19. In an edge setting machine, a holder, a tool, a pivotal bearing between said holder and said tool, comprising a recess, a knife edge contacting one portion of said recess, and a bearing surface contacting another portion of said recess.

20. In an edge setting machine, a holder having a knife edge and a recess, and a tool having a recess and a lug, said lug contacting the wall of said former recess when said knife edge is positioned in said second recess.

21. In an edge setting machine, a holder, a tool, one of said elements having a notch, a knife edge on the other of said elements adapted to rest in said notch, whereby the holder and the tool may pivot on each other, and a second contact element on each of the tool and the holder, said latter contact elements when in contact preventing the disengagement of said notch and said knife edge, but separating when said holder and said tool are sufficiently relatively rotated to permit the disengagement of said notch and knife edge.

22. In an edge setting machine, a holder, a tool, a contact element on each which permits a pivotal motion between the holder and the tool, and second contacting elements on each of the holder and the tool whereby the former two contact elements are held in contact during the pivotal motion.

In testimony whereof I have signed my name to this specification in the presence of two subscribing witnesses.

FRANK BYCROFT KEALL.
